CLAIM

The ornamental design for an ice cream holder, as shown and described.

DESCRIPTION

FIG. 1 is a top plan view of an ice cream holder showing my new design, it being understood that the undisclosed bottom of the horizontal surfaces are flat and unornamented;

FIG. 2 is a side elevational view thereof, the broken undisclosed sides being the same and the broken lines shown are for illustrative purposes only, forming no part of the claimed design; and,

FIG. 3 is a top perspective view thereof.
